COMBINATION READING STAND AND
BOOK CARRIER

James J. Sampson, Waterloo, Iowa

Application November 20, 1939, Serial No. 305,327

2 Claims. (Cl. 45—57)

My invention relates to improvements in combination reading stands and book carriers, and the principal object of my improvements is to supply a portable collapsible device adaptable for receiving a book or books or an object or objects of similar shape and proportions, and which, when extended and adjustably positioned for use, may support thereon a book or books or other objects as a reading stand or easel.

Another object of my improvements is to combine with the mechanical elements of the device a flexible and suitably patterned covering element connected thereto, to provide a cover or foldable casing therefor, and suitable as a pliable mounting upon which the stand is supported when extended for use.

I have accomplished the above objects by the means and mechanisms which are herein described and claimed, and which are illustrated in the accompanying drawings, it being understood that various modifications in the details of construction and arrangement of parts of the apparatus and its connections may be made without departure from the principles and scope of the invention as defined in the following claims.

In the drawings, Fig. 1 is a top plan of the flexible covering as spread on a flat surface, with the relatively movable elements of the stand and book cover collapsed flatly thereupon, with portions of said covering removed or broken away. Fig. 1a is a front elevation of a top hinge member. Fig. 2 is a perspective view of the easel or book supporting means as mounted on the spread pliable mounting, and presenting the rear of the supporting means in an angularly adjusted and propped position, and on a smaller scale than used in said Fig. 1. Fig. 3 is a front elevation of the easel members of the device as erected and supporting thereon an alined pair of opened books, together with a third opened book clipped to the upper structures of the device above said pair of books. Fig. 4 is an end elevation of the apparatus extended as in Fig. 3. Fig. 5 is an enlarged detail of the lower parts of the easel member, including parts of the book carrying front ledge, with other parts broken away. Fig. 6 is an enlarged detail or under plan of one of the book carrying ledge pairs with an opened book thereon. Fig. 7 is an end elevation, on a smaller scale, of a pair of books inclosed in the collapsed holder device and cover, and Fig. 8 is a view of a face of the partially collapsed flexible cover.

Referring first to said Fig. 1, the numeral 1

denotes a flexible cover for the apparatus, as spread out flatly, whose body is oblong with one end 7 angular and supplied with a snap means at 8. Adjacent said end part are like flaps 11 and 11a projecting oppositely laterally from the main body of the cover and having snap connecting means terminally for coaction, as shown at 4 on 11a. Other fastener elements are shown at 9 in the right hand end part of the cover.

The stand rigid members as connected are in like pairs of basal devices 5 and 5a of U-shape and respectively clamped to the cover 1 by socketed receiving members 6, 6a, and other like members such as shown at 6g and also like members on the cross parts of said devices. Open rectangular wire members, shown at 12 and 12a are medially spaced apart, and their lower horizontal reaches traverse bearings 6b and 6d respectively mounted on said cover 1, while said lower reaches are rockably mounted in eyes on the extremities of the U-shaped members 5 and 5a, thus hinging the members 12 and 12a thereto.

The members 5 and 5a, being spaced apart from each other medially, I have supplied means for hinging their inner vertical reaches together to permit said members to be swung into spaced parallelism, when the device is to be collapsed together with the cover 1. Alined horizontal vertically spaced pairs of bars 15 and 15a, and 19 and 19a are terminally secured across said members 12 and 12a, and also medially secured to medial cross braces 29 and 29a between the upper reaches of said members and the bars. The inner and outer extremities of the said bars are shaped with sockets respectively at 20—21, and 20a—21a, also at 17—18, 18a—17a, and are terminally medially notched at 20—21, and 21a—20a. The opposed ends of the sockets or bearings 21 and 21a have pintles seated therein crossing the notches, and a cross-bar 22 has its opposite ends connected to the pintles in the notches, to provide medial hinges between the bars 19 and 19a.

45 C-shaped rods 13 and 13a, relatively reversed in position, are respectively hinged at 20—25b and likewise at 20a and 25a to the outer vertical reaches of the members 12 and 12a, while the cross bars 25 and 25a respectively are fixedly mounted at their outer ends to the middle parts of the members 13 and 13a.

Both pairs of members 13 and 13a are pivoted to the upper reaches of the members 12—12a by cupped devices 27 having forward spaced in-turned flanges 26 in which are rockably mounted

opposite parts of the members 13 and 13a associated with end parts of the members 12 and 12a respectively, and the devices 27 also have downwardly bent fingers 28 which close the gaps between said flanges above and across them. The hinge joints permit the outer frames to be moved through an angle of 90 degrees with respect to the inner frames so that they may either be aligned with the inner frames or be disposed normal thereto, and cannot be dislodged by any ordinary shocks. The upturned extremities of the lower members of the frames 13 and 13a are rockably seated in the end sockets 17 and 17a of said inner frames 15 and 15a respectively. The bars 15—15a are thus linked to the bars 16 and 16a, and the latter are fixedly mounted on the outer frames 13 and 13a.

The inner spaced vertical reaches of the frames 12 and 12a are at their tops seated in like socket 27 and receive also, pivotally, the down-turned ends of the upper connection 14, and a spring clip U-shaped plate 30a—30 mounted fixedly on the reach of the member 14, has an adjustable screw connection 31 between its parts, to serve as a holder for a book or other device as shown at 32. A link 14a has upturned members seated in the sockets 18 and 18a of the lower bars 15 and 15a, and its reach is rockably mounted in a bearing member 6f secured upon said cover 1.

Referring to said Fig. 2, the frames above described are shown as extended rockably upon the bearing members 5—5a, the numerals 24 and 24b denoting a like pair of rear props of C-shape hinged terminally to the upper bars 19a and 19, and whose middle reaches are arched inwardly at 24a to span the foundation outer side reaches of the props, adjustably, in varying the rearward inclination of the said easel members. In Fig. 4 is shown an end elevation of the base frame showing the outer end of an easel member erected angularly thereon and supported by the adjustably swingable prop 24b whose free outer angles may releasably engage the stop 6 or 6g to vary the inclination of the easels rearwardly. As shown in Fig. 6, flange members 36 and 36a, are fixed to extend forwardly from the lower reaches of the members 12 and 13 to serve as ledge supports or holders for a book 34, whether opened or collapsed. Fig. 5 is a front elevation of said ledge members.

In Fig. 3 is shown a pair of opened books 34 and 35 supported on the ledges 36—36a respectively, while the upper clip members 30a support a smaller book 33, or a pamphlet of few leaves.

Fig. 7 shows two volumes of books as seated clampingly between the frames 12 and 12a as swung inwardly toward each other in parallelism, spaced apart, and showing the flexible cover 1 partially inclosing the books and their collapsed members including the end frames 13 and 13a folded upon each other. The books rest edge-

wise upon the inner frame connections 14a. Fig. 8 shows the cover 1 as collapsed together about the frames, with one end flap extended.

It will be seen, that my invention is portable when collapsed, and it is also evident that instead of two sets of easel members including the end members 13 and 13a, a single easel with hinged side members, or without such side members, contain the operativeness of the coupled devices shown, in the receiving, and supporting of an easel with its rear adjusting prop, its skeleton base members, and the flexible cover which is conformable to the collapsed device for storage or transportation whether carrying an article within or not.

I claim:

1. In a device of the character described, a portable book-holder, comprising in combination, a flexible cover, rigid like basal members fastened upon said cover, like spaced pairs of skeleton easels spaced apart longitudinally and hingedly foldable upon said basal members with the latter spaced apart and also hingedly foldable together with said cover, the easels also including end-hinged extension members also foldable upon and connected to said cover pivotally, U-shaped props on the rear parts of the skeleton easels and end-engageable with parts of the basal members when the props are extended adjustably, a plurality of linking rigid cross connections between the inner parts of the easels for permitting the respective members of the easels to be spaced apart when collapsed in parallelism for supporting articles fitted between them, and means for hingedly connecting an adjacent one of the cross connections to the cover.

2. The combination, in a foldable carrier, of longitudinally spaced horizontally disposed base members, longitudinally spaced easel members hingedly connected to the base members in transverse alignment therewith, transversely spaced linking devices positioned between and end-pivoted to the opposed side parts of the easel members, like end members hingedly linked to the outer end parts of said easel members the hinges connecting the end members to the easel members having stop devices thereon permitting rotation of the end members between fixed positions forwardly and inwardly toward the easel members, sectional longitudinally aligned shelf parts fixed to project forwardly on the lower parts of the easel members and said end members, each of the base members having transversely spaced stops mounted therealong, and loop-shaped rearwardly directed props hingedly supported longitudinally on the easel members adapted to swingably engage adjustingly said spaced stops releasably to support said easel members tiltably.

JAMES J. SAMPSON.
